UNITED STATES PATENT OFFICE

96,614

DESIGN FOR A FROZEN CONFECTION OR SIMILAR ARTICLE

Harold W. Law, San Francisco, Calif.

Application May 7, 1935, Serial No. 56,721

Term of patent 14 years

To all whom it may concern:

Be it known that I, Harold W. Law, a citizen of the United States, residing at the city and county of San Francisco and State of California, have invented a new, original, and ornamental Design for a Frozen Confection or Similar Article, of which the following is a specification, reference being had to the accompanying drawing, forming a part hereof.

In the drawing Fig. 1 is a front view of a frozen confection or similar article substantially full-size, showing my new design.

Fig. 2 is a side or edge view of the confection.

Fig. 3 is a bottom view of the confection.

I claim:

The ornamental design for a frozen confection or similar article, substantially as shown and described.

HAROLD W. LAW.
